UNITED STATES PATENT OFFICE.

HENRY L. TRUDEL, OF IPSWICH, MASSACHUSETTS, ASSIGNOR, BY MESNE ASSIGNMENTS, TO SCOTT & WILLIAMS, INCORPORATED, OF CAMDEN, NEW JERSEY, A CORPORATION OF NEW JERSEY.

THREAD CUTTER AND HOLDER FOR CIRCULAR-KNITTING MACHINES.

1,191,100.

Specification of Letters Patent. Patented July 11, 1916.

Application filed March 24, 1910, Serial No. 551,306. Renewed November 14, 1912. Serial No. 731,431.

To all whom it may concern:

Be it known that I, HENRY L. TRUDEL, a subject of King Edward VII of England, residing at Ipswich, in the county of Essex 5 and State of Massachusetts, have invented new and useful Improvements in Thread Cutters and Holders for Circular-Knitting Machines, of which the following is a specification.

10 This invention relates to circular knitting machines for knitting stockings, the circular knitting machines being of that particular class which are adapted to knit a reinforced sole and heel portion and in which two 15 threads are knit across the bottom of the sole and heel portion of the stocking, and one of the threads is carried across the top of the foot portion of the stocking in each course, but is not knit in with the other 20 thread.

The object of the present invention is to provide a simple and efficient device which will automatically cut and hold the auxiliary thread after each course of stitches 25 has been knit across the bottom or sole portion of the stocking, and to hold said thread while that portion of the stocking is being knit which extends across the top of the foot in each course.

30 In the present case I have illustrated my invention as applied to a machine of the character which is fully illustrated and described in patents to J. D. Hemphill No. 935,981, October 5, 1909, and 933,443, September 7, 1909, to which reference may be had for a complete understanding of the entire machine, so much thereof being shown and described in the present case as is necessary to understand the application of my 35 invention to this particular form of machine. This embodiment of my invention is applied to a machine having a rotary needle carrier or cylinder and sinker ring, but the same is also applicable to a machine having 40 a stationary needle cylinder and rotary needle cam carrier.

The invention consists in the combination and arrangement of parts set forth in the following specification and particularly 45 pointed out in the claims thereof.

50 Referring to the drawings: Figure 1 is a plan view, partly broken away to save space,

showing my invention in connection with the needle cylinder, sinker ring and other parts of the machine. Fig. 2 is a detail sectional elevation taken on line 2—2 of Fig. 1. Fig. 3 is a side elevation of the same as viewed from the right of Fig. 1. Fig. 4 is an enlarged sectional elevation taken on line 4—4 of Fig. 1, looking in the direction of the arrows on said line. Fig. 5 is a detail sectional elevation taken on line 5—5 of Fig. 4, as viewed in the direction of the arrows on said line. Fig. 5^a is a detail perspective of the cutter and clamp blades. Fig. 6 is a detail sectional elevation taken on line 6—6 of Fig. 4 as viewed in the direction of the arrows on said line.

Like numerals refer to like parts throughout the several views of the drawings.

In the drawings, 10 is the frame of the machine, 11 the main driving shaft, 12 a cam shaft, 13 the needle cylinder, 9 the needle cam ring, 14 the needles, 15 the rotary sinker ring, 16 the sinker cam ring 75 and 17 the latch ring, all of these parts and their mode of operation being clearly shown and described in said Letters Patent.

18 is a primary thread guide and 19 an auxiliary thread guide. During the knitting of the foot portion of the stocking, the primary thread guide 18 remains in operative relation with the needles, in the proper position to lead the thread thereto throughout the knitting of each course, but the auxiliary thread guide 19 is thrown into and out of action during each course of the knitting of the foot portion, so that the sole and heel of the stocking will have two threads in each course while the top of the 90 foot portion will have only one thread knit thereacross.

The auxiliary thread guide 19 is held normally in action by a spring 20 and is moved out of action by a lever 21 connected by a link 22 to a lever 23, and this lever 23 may be thrown upwardly at its left hand end (Fig. 3) by a cam 24 which is of sufficient length to hold said lever with its left hand end raised while that portion of the stocking which contains a plurality of courses composed of a single thread is being knit. The auxiliary thread guide 19 is operated for each course of the foot portion to throw

the same into and out of action by a cam 59 on the main shaft 11 which operates a lever 60 which engages the rod 22 and lowers the rod to throw the auxiliary thread guide 5 out of action and raises said rod to allow said auxiliary thread guide to be thrown into action by the spring 20, it being understood that this cam acts to throw the auxiliary thread guide into and out of action alternately 10 while the foot portion of the stocking is being knit, so that the stocking will be knit with a double sole.

The thread is cut and held by a severing device or shears 25 which are located 15 within the circle of the series of needles 14. These shears are illustrated in detail in Figs. 5 and 6 and consist of a movable member formed by a blade 26 and a holding plate 27 joined together by a screw 28 20 and a spring-tension bolt 29, the screw 28 being fastened to a lever 30 and extending through a slot 31 in the stationary member 32, while the bolt 29 extends through a slot 33 in said stationary member.

25 A slot 34 for the reception of the thread 35 to be severed and held, is alternately opened and closed by the movement upwardly and downwardly, respectively, of the movable cutter and holder blades 26 and 30 27, and by reference to Fig. 5 and Fig. 5a it will be seen that the lower edge of the cutter blade 26 is beveled to coact with the beveled lower edge of the slot 34, and that the lower edge of the holding blade 27 is rounded off so as not to cut the thread, but to hold it as illustrated in Fig. 5.

The lever 30 is pivoted upon a stud 36 fast to a bracket 37 which, in turn, is fastened to the latch ring 17. Said lever 30 is rocked 40 by a pin 38 which projects into a slot 39 in the outer end of said lever. The pin 38 is fast to a slide 40 adapted to be moved vertically and guided by a pin 41 and screw 42 which project through slots in said slide 40 45 and are each fastened to another slide 43 which is adapted to slide in a direction radial to the center of motion of the machine upon screws 44 fast to a standard 45 which is, in turn, fastened to the stationary bed- 50 plate 46. A spring 47, fast at one end to the pin 41 and at the other end to a pin 48 on the slide 40, acts to hold said slide normally in its uppermost position.

A cam follower roll 49 is rotatably mounted 55 upon the slide 40 and bears normally against the under side of the sinker ring 15. The same is engaged twice during each rotation of the needle cylinder and the sinker ring by cams 50 and 51 which act to move the slide 40 downwardly against the action of the spring 47 twice during each successive course knit in the foot portion of the stocking. The slide 40 constitutes a movable element or connection capable of connecting the 60 yarn cutter and clamp mechanism to its ac-

tuating cams, which give the slide 40 a downward movement. This downward movement rocks the lever 30, moving the movable member of the shears upwardly, uncovering the slot 34 and allowing the thread to enter 70 the same, and when the cam 50 releases the roll 49 and its slide 40, the slide will be drawn upwardly, thus rocking the lever to allow the movable portion of the shears to move downwardly and cut off the thread 75 and hold the same clamped within the slot 34.

It will be noticed that the cams 50 and 51 are relatively fixed with respect to the needles. They therefore determine with respect to the fabric at what point around the tube of knitting the yarn is to be cut. By timing the actuation of the cutter and clamp in this manner from a part moving with the needles I am enabled to cut and clamp the 80 yarn accurately at the borders of the sectional splicing. This is further aided by the position of the depending or fixed blade of the shear cutter constituted by the part 32, which it should be noticed is near the 85 back of the needles and very close to the forming edge of the fabric. The cut end of the yarn left attached to the fabric is therefore as short as the practicable dimensions of the cutting elements will permit. 95

When that portion of the stocking is reached in which only a single thread is to be used, the slide 43, which carries with it the slide 40, is moved toward the right (Fig. 4) and the pin 38 moves out of the slot 39, 100 while the roll 49 moves out of engagement and alinement with the cams 50 and 51, so that for a plurality of successive courses the slide 40 will be out of action and consequently the lever 30 and the shears will be 105 out of action, while the end of the severed thread will be held by the blade 27. The slide 40 is moved, together with the slide 43, radially outward from the center of the needle cylinder for this purpose by means of a lever 52 which is pivoted at 53 to the standard 45, said lever being connected to the slide 43 by a screw 54, and the lower end of said lever being connected by a link 55 to a bell-crank lever 56 which, in turn, is connected by a link 57 and a screw 62 entering a short lost-motion slot 63 in said link to a bell-crank lever 58 which is rocked upon its pivot 61 by the rod 22 to which it is connected. The rod 22 when moved by the 110 cam 24 to withdraw the auxiliary or sectional splicing guide 19, when knitting of like character is to be done throughout an entire course or plurality of courses, as for the leg of a stocking, is moved a sufficient 115 distance by cam 24 to bring screw 62 against the end of slot 63 and remove slide 43 radially, to break the connections 38, 39 and 49, 50, and thus to cease operating the cutter and clamp. When cam 24 releases le- 120 125 130

ver 23, spring 20 causes rod 22 to move upward, shifting lever 60 into contact with cam 59. When the low part of said cam is in contact with lever 60, rod 22 and bell-crank 58 will be in a position bringing screw 62 against the right end of slot 63, as shown in Fig. 3, to move slide 43 inward to the position shown in Fig. 4, to reestablish the connection to the clamp and cutter. Rod 22, lever 21, and yarn-guide 19 are now operated twice in each revolution by cam 59, through a less distance than the motion imparted by cam 24, but sufficiently to cause the auxiliary guide to enter and remove its yarn from the needles. During this movement screw 62 traverses slot 63 without moving link 57 or the slide 43.

The general operation of the machine hereinbefore specifically described is as follows: Thread is led to the needles by the primary thread guide 18 and this thread guide leads thread to the needles while both the top and sole portion of the foot of the stocking is being knit, or, in other words, throughout the entire extent of the courses. Another thread is led to the needles 14 by the auxiliary thread guide 19. This auxiliary thread guide, during the knitting of the foot portion of the stocking, is operated to throw the same into and out of action relatively to the needles alternately during each course that is knit, and this movement of the auxiliary thread guide is accomplished by the mechanism hereinbefore described. The thread cutter and holder 25 is also operated twice during each course knit, of the foot portion of the stocking, in the following manner: The cams 50 and 51 alternately engage the roll 49 upon the slide 40 and move the same downwardly (Fig. 4), thus rocking the lever 30 upon its pivot 36 and moving the cutting blade 26 and holding blade 27 upwardly to open the slot 34. This is done in proper time so that as the needle cylinder rotates, carrying with it the needles 14, and while the auxiliary thread guide is in its raised or inactive position, the thread is carried by the rotation of the cylinder and its needles into the slot 34, as illustrated in dotted lines Fig. 1. As soon as the thread gets into the slot 34, the cam 50 or 51, as the case may be, releases the slide 40 and the spring 47 moves said slide upwardly, causing the lever 30 to be rocked upon its pivot to move the cutter and holder blades 26 and 27 downwardly, thus cutting off the thread and holding the same until the auxiliary thread guide is thrown down into position to lead thread to the needles again, and the cam 51 then releases the thread which has been held by the holding blade 27, so that in each course of the foot portion of the stocking, two threads are led to the needles while the sole portion of the stocking is being knit, and one thread is

led thereto while the top of the foot portion is being knit and the auxiliary thread is automatically cut off and led to the needles alternately during each course which is knit into the foot portion of the stocking.

After that portion of the stocking is knit where the reinforced part is employed or in which a second thread is knit into the stocking, it is desirable to knit a certain part of the stocking, or the next succeeding stocking, that is, the leg portion or ankle portion, without the use of the auxiliary thread, and, therefore, it is necessary to hold the auxiliary thread guide out of action and the cutter mechanism out of action while a plurality of successive courses is being knit with a single thread, or without the auxiliary thread hereinbefore referred to. This is accomplished by the cam 24 acting to rock the lever 23 and, through the rod 22, to raise the auxiliary thread guide out of action. At the same time the lever 58 is rocked by said rod 22 to actuate the link 57, thus actuating the link 55 to rock the lever 52 toward the right (Fig. 4) and move the slide 43 and slide 40 toward the right, thus disconnecting the pin 38 from the slot 39 in the lever 30, so that the cutting mechanism is out of action and also the roll 49 is thrown out of the path of movement of the cams 50 and 51. When the cam 24 has passed by the lever 23, the reverse of the movements hereinbefore described will occur and the auxiliary thread guide will be thrown into action and the cutting device and its actuating mechanism thrown into position to be actuated by the cams 50 and 51 at each rotation of the needle cylinder.

It will be noticed that the described movement radially outward of the slide 43 breaks the connection between the lever 30 and its actuating mechanism. This permits the free elevating movement of the latch ring 17 about its pivot 171 in the ordinary operation of the machine shown in the said Hemphill patents. My device therefore provides means to cut and clamp the splicing yarn carried by the latch ring and free to be moved away from the needles with said latch ring, without placing upon the latch ring any part of the operating connections for the cutter and clamp except the lever 30 and the bracket upon which it is pivoted.

Having thus described my invention, what I claim and desire by Letters Patent to secure is:

1. A knitting machine having in combination with a rotary knitting element a sectional splicing device comprising a plurality of yarn guides, a movable connection for rendering one of said yarn guides operative and inoperative during each revolution of said element, a yarn severing mechanism, means for actuating said severing

- mechanism during each revolution, and means actuated by said connection for rendering said severing means inoperative.
2. In a knitting machine a needle cylinder and needles, yarn feeding means including a pivoted latch guard ring, means to clamp and cut a yarn removed from operative feeding position mounted on said latch rings, and actuating means for said cutting and clamping means including an element movable into and out of engagement with said cutting and clamping means, whereby the latch guard ring may be elevated freely when said means are disengaged.
3. In a knitting machine a needle cylinder and needles, yarn feeding means including a pivoted latch guard ring, means to clamp and cut a yarn removed from operative feeding position mounted on said latch ring, and actuating means for said cutting and clamping means including an element movable into and out of engagement with said cutting and clamping means whereby the latch guard ring may be elevated freely, and means for moving said element into and out of engagement with said cutting and clamping means at predetermined times.
4. In a yarn feeding device for knitting machines, in combination with a needle cylinder and needles therein, a movable yarn guide and means to move it at predetermined times from an operative position at the exterior of the knitting needles to an inoperative position above and toward the interior thereof, a latch guard ring, a relatively fixed yarn severing member mounted upon said ring having a depending portion within the circle of needles, said depending portion having a channel or notch therein to receive yarn from a yarn guide in an inoperative position, severing means for said yarn coöperating with said depending member, means independent of said latch guard ring to operate said cutting and holding means, and means to render said operating means inoperative at predetermined times.
5. In a knitting machine, a sectional splicing device comprising a plurality of yarn guides, a cam shaft and pattern cams, and connections for rendering said yarn guides operative and inoperative, means coöperating with one of said connections for independently rendering one of said guides alternately operative and inoperative when permitted by its pattern-cam, a yarn-severing mechanism, and means for actuating said mechanism rendered operative and inoperative by the movement of said connection.
6. In a knitting machine, yarn guides and means to move them independently including a cam-shaft and pattern cams, means to sever the yarn from a yarn guide in an inoperative position and actuating means for said severing means comprising an element and connections thereto controlled from said cam-shaft to move said element into and out of operative engagement with said severing means in combination with means to operate said element when it is in operative engagement with said severing means.
7. In a knitting machine, needle and cam carriers, means to rotate one of said carriers with respect to the other, yarn-guides and means to move them independently including a cam-shaft and pattern cams, means to sever the yarn from a yarn guide in an inoperative position and actuating means for said severing means comprising an element and connections thereto controlled from said cam-shaft to move said element into and out of operative engagement with said severing means in combination with means relatively fixed with respect to said needle carrier to operate said element when it is in operative engagement with said severing means.
8. In a knitting machine, knitting needles, yarn feeding means including a plurality of yarn guides and means to render one of them active and inactive at predetermined times, a yarn severing mechanism positioned to encounter yarn from a yarn guide in an inoperative position and means to actuate said severing mechanism, said means including an element movable into and out of operative engagement with said severing mechanism, and a cam relatively fixed with respect to the knitting needles in a position to encounter said element when in said operative engagement only, to then operate said severing mechanism.
9. A circular knitting machine having, in combination, a needle cylinder, a series of needles mounted thereon, a thread guide adapted to lead thread to said needles, shears adapted to cut and hold said thread within the circle of said needles, a slide adapted to operate said shears, means movable with said needle cylinder adapted to actuate said slide to operate said shears, a second slide upon which said first named slide is mounted and means to move said last named slide to carry said first named slide out of engagement with said actuating means.
10. A circular knitting machine having, in combination, a rotary needle cylinder, a series of needles mounted thereon, a primary thread guide and an auxiliary thread guide adapted to lead thread to said needles, means adapted to move said auxiliary thread guide into and out of coöperative relation with said needles, for each course of a plurality of successive courses knit thereby, shears adapted to cut and hold said thread within the circle of said needles, a slide adapted to operate said shears, and means movable with said needle cylinder adapted to actuate said slide to operate said

shears twice while said needles are knitting a single course, and means adapted to hold said auxiliary thread guide out of operative engagement with said needles and said slide 5 out of engagement with its actuating means while a plurality of courses are being knit upon said needles.

In testimony whereof I have hereunto set my hand in presence of two subscribing witnesses.

HENRY L. TRUDEL.
